MULTIPLE COMPARTMENT PAIL

Filed Jan. 29, 1930

FIG. 1

FIG. 2

FIG. 3

Inventor
BERTHA M. ESSLINGER

By: *Ben V. Zillman*

Attorney

UNITED STATES PATENT OFFICE

BERTHA M. ESSLINGER, OF ST. LOUIS, MISSOURI

MULTIPLE COMPARTMENT PAIL

Application filed January 29, 1930. Serial No. 424,154.

My invention relates to improvements in pails, and more particularly to pails having a plurality of compartments therein, and has among its objects the production of such pails which shall be neat and attractive in appearance, simple and sturdy in construction, compact, reliable, and efficient and satisfactory for use wherever found applicable.

The ordinary pail, as is well known, comprises but a single compartment, so that when one desires to do any cleaning in the household, store, office, or elsewhere, it is necessary to use at least two such pails, one of which contains the clear water and the other of which contains the dirtier water or other cleansing solution. To carry two or more of such pails about is quite bothersome, and in some instances, as for example when one is cleaning from a ladder, there is no room for more than a single pail upon the ladder, and hence one must constantly go up and down the ladder to the clean-water pail at the foot of the ladder, when doing such cleansing.

To overcome these objectionable features of the single compartment pail, I have so constructed a pail that it will have a plurality of liquid-containing compartments.

With my improved construction, the different waters or solutions may be carried about in the single unit, thereby enabling the user to have the complete cleansing outfit with him at all times and in all places desired to be cleansed.

Another object of my invention is to provide a container of the kind described, and wherein the inserts forming the multiple compartments shall have individual handles for the easy removal or withdrawal from the outer pail.

A further object of my invention is to form an article of the kind described, which shall form the multiple-compartment pail from the ordinary pail now in common use.

Many other objects and advantages of the construction herein shown and described will be obvious to those skilled in the art to which this invention appertains, from the disclosures herein given.

To this end, my invention consists in the novel construction, arrangement and com-

bination of parts herein shown and described, and uses mentioned, and more particularly pointed out in the claims.

In the drawings, wherein like reference characters indicate like or corresponding parts throughout,

Figure 1 is a perspective view of one form of my improved construction;

Figure 2 is a cross-sectional view of the same, taken substantially along the line 2-2 of Fig. 1; and

Figure 3 is a perspective view of a modified form of the invention.

Referring more particularly to the drawings, wherein I have illustrated the preferred embodiment of my invention, A represents any suitable type of pail or container, and in the present instance is shown to be the ordinary, commonly-used household bucket or pail, the same being generally provided with a handle or bail 1, somewhat as shown.

In the embodiment of the invention shown in Figs. 1 and 2, the pail is divided into the plurality of independent separate compartments 3-3 by means of a partition wall member 4, extending radially within the pail from the bottom of the same to adjacent the top thereof. The partition may be secured to the inner surface or wall of the pail in any suitable manner, as by riveting, welding, etc., and in order to secure a better contacting surface along the bottom and side walls of the partition, whereat the latter is joined to the pail, the partition may have flanged edges, somewhat as indicated in the drawings, 85 wherein 5 indicates the bottom flange and 6-6 the side edge flanges. The side flanges 6-6 may be directed in mutually opposite directions of desired, as shown.

The cleaning solution may be kept in one of the compartments thus formed within the pail, and the other compartment may be used for containing the rinsing solution, these compartments being wholly independent of one another, with no possibility of the solution from one compartment running into the other compartment.

In the modified form of the invention illustrated in Fig. 3, there is no permanent alteration of the outer pail, and in this instance,

said pail is used merely as a holder or container for the container inserts.

5 One or more insert members B are removably positioned within the outer pail A, each of these insert containers having a radially extending partition wall 7 and bottom and side walls to form a segmental-shaped container. The insert containers are merely dropped into the outer pail A as shown, to thereby form the plurality of independent, 10 separated compartments.

15 In order to facilitate the removal of the inserts from the pail, handles 8 are formed at the top thereof, preferably at the partition wall, the handles of the adjacent inserts being arranged to lie in juxtaposition to form in effect a single handle, so that both of the individual handles may be grasped together for the simultaneous removal of both inserts 20 from the pail.

25 Having thus described my invention, it is obvious that various immaterial modifications may be made in the same without departing from the spirit of my invention; hence I do not wish to be understood as limiting myself to the exact construction, form, arrangement and combination of parts herein shown or described, except as necessitated by the prior art.

30 What I claim as new and desire to secure by Letters Patent is:

35 1. An article of the kind described and in combination, a pail, and a partition therein to divide the same into a plurality of independent compartments extending from top to bottom of the pail, said partition having its side and bottom edges flanged and secured to said pail along said flanges.

40 2. In an article of the kind described and in combination, a pail, and means for insertion into said pail for dividing the same into a plurality of independent compartments extending from top to bottom of the pail, said means consisting of a partition having integral flanges at the sides and extending in mutually opposite directions, said partition being secured to said pail along said flanges.

45 3. In an article of the kind described and in combination, a pail, and a partition for dividing the same into a plurality of separate compartments extending the full length of the pail, said partition having oppositely extending integral side flanges, and an integral bottom flange, and secured to the pail along 50 all of said flanges.

55 BERTHA M. ESSLINGER.
